FAN BLADE AND HUB ASSEMBLY OR
SIMILAR ARTICLE

Lawrence L. Alldritt, 59 NW. 14th St., Miami, Fla.

Filed Sept. 3, 1959, Ser. No. 57,423

Term of patent 14 years

(Cl. D26—7)

FIG. 1.

FIG. 2.

FIGURE 1 is a side elevational view of a fan blade and hub assembly or similar article, showing my new design;

FIGURE 2 is a cross-sectional view in a different position, taken on the line 2—2 of Figure 1;

FIGURE 3 is a top plan view on a reduced scale;

FIGURE 4 is a perspective view on a reduced scale; and

FIGURE 5 is a cross-sectional view of one of the three identical blades, taken on line 5—5 of Figure 4.

The design is characterized by the leading and trailing edges of the structure shown in full line being spaced apart a distance substantially greater than the width of the full line structure; and the design is also charac-

terized in that the structure shown in full line cannot be viewed edgewise when looking perpendicular to the axis of rotation, but only obliquely.

I claim:

The ornamental design for a fan blade and hub assembly or similar article, as shown and described.
